Des. 191,368
Patented Sept. 19, 1961

191,368

TEA BAG HOLDER

Nori Sinoto, 345 W. 58th St., New York, N.Y.

Filed Sept. 27, 1960, Ser. No. 62,278

Term of patent 3½ years

(Cl. D44—24)

FIG. 1 is a perspective view of a tea bag holder, showing my new design;

FIG. 2 is a side elevational view thereof;

FIG. 3 is a front elevational view thereof; and

FIG. 4 is a top plan view thereof.

I claim:

The ornamental design for a tea bag holder, substantially as shown.
